SHOE SEWING MACHINE

Raymond E. Hopkins, Rockland, Mass., assignor to United Shoe Machinery Corporation, Flemington, N. J., a corporation of New Jersey

Original application November 1, 1938, Serial No. 238,184. Divided and this application December 2, 1940, Serial No. 368,194

7 Claims. (Cl. 112—50)

The present invention relates to improvements in machines for manufacturing shoes.

The object of the present invention is to provide a machine for use in the manufacture of a strong and durable shoe of attractive appearance, resembling a Goodyear welt or turn shoe, but capable of being made of cheaper materials and without the use of the expensive machines and skilled labor necessary for the production of Goodyear shoes.

The shoe and the method of making it form the subject matter of pending application Serial No. 238,184, filed November 1, 1938, of which the present application is a division. The final shape of this shoe is based on the outline of a channel or a lip on an insole, or in the case of a turn shoe, on a sole, by utilizing the lasting process of Goodyear shoe making methods having the upper properly shaped and fitted over a last, and preliminarily secured to the insole or sole, without further weakening of those portions the section or strength of which has already been reduced in forming the lip.

The manufacture of the shoe above referred to includes working the shoe upper into a lasted position over the marginal portions of a sole in the case of a turn shoe, or the insole in the case of a welt shoe, the sole or insole having an upstanding rib or lip; securing the marginal portions of the upper to the lip by means of preliminary fastenings and, in order to do away with the necessity of using a Goodyear welt and turn shoe sewing machine, and to permanently secure the parts of the shoe together, a line of fastenings is inserted outside of the lip of the sole or insole, conveniently using for this purpose a shoe sewing machine of the McKay type, which type of machine can readily be maintained in proper adjustment and operated at a high rate of speed by a workman lacking the necessary high degree of skill and long experience required in a Goodyear operator.

In order to insure the location of the line of permanent fastenings entirely outside of the lip of the sole or insole, the operation of the McKay type sewing machine is directed, as hereinafter described, by engaging the inner surface of the lip on the sole or insole, thus determining the final shape of the shoe in the same manner as in a Goodyear welt shoe. One advantage of this construction is in a stronger inseam than when sewed through the base of the lip, and in the possibility of using low grade materials without appreciably lowering the quality or strength of the finished shoe. Another advantage in manu-

facturing the shoe by these methods is that the lip on the sole or insole may be trimmed closer than heretofore, due to the spacing of the inseam from the lip and, if desirable, the preliminary lasting fastenings may also be removed without danger of injuring the permanent inseam.

In the manufacture of the shoe above referred to, a sole or insole of thinner stock may be employed than can be used for the construction of a Goodyear welt shoe, and the lip to which the preliminary fastenings are inserted and by which the permanent line of fastenings is guided may be formed by securing a separate strip of material to the marginal portions of the sole or insole or by forming an inclined cut or channel at an angle to the surface of the sole or insole in the usual way.

In the construction of a Goodyear welt or a turn shoe it is usual to form a channel before assembling the insole on a last, further from the edge of the insole along the shank than along the forepart so that when the upper is permanently sewed to the base of the channel lip, the shoe will retain its original shape and less strain than heretofore will be imparted locally to the individual parts of the completed shoe while in use. In the manufacture of the shoe above referred to, the formation of the channel in this way results in the added advantage of a stronger inseam which is less yielding than with an inseam inserted at the base of the channel lip as in the Goodyear method.

For the sake of convenience in sewing, rather than cementing the outsole, according to a further feature of the invention, a welt strip may be directed into the seam which connects the upper and insole so that the parts will be joined securely together. Preferably, the inner sewed edge of the welt is so positioned that it is out of contact with the lip after attachment to permit trimming the lip without disturbing the welt. The outsole may be sewed on an ordinary outsole stitcher, the subsequent operations following the procedure employed in completing a Goodyear welt shoe.

The improved machine embodying the present invention is provided with a straight hook needle, a work supporting horn, a presser-foot acting on the work in the line of the seam, and a channel guide having its entire work engaging portion acting at the inside of the seam line opposite to the outer edge of the insole. This feature of the invention also contemplates the provision of a welt guide arranged to direct the welt strip into

the seam with the greater portion of the strip opposite to the channel guide. In order to insure that the channel guide will be retained in contact with the channel lip while guiding the seam, the channel guide is mounted for relative movement on the presser-foot so that when the presser-foot is raised, while feeding the work, the channel guide will not be retracted from the lip, this arrangement of the channel guide being advantageous whether the machine is provided with a welt guide or not. 10

Other features of the invention will become apparent to those skilled in the art from a consideration of the following description, taken in connection with the accompanying drawing, in which: Fig. 1 is a view in front elevation illustrating the relationship of the parts of a shoe with certain parts of a sewing machine embodying features of the present invention; Fig. 2 is a plan view of the presser-foot and channel guide of the machine shown in Fig. 1; Fig. 3 is a view in side elevation of some of the parts shown in Fig. 1, looking from the right; Fig. 4 is a top plan view, on a reduced scale, of a shoe sole as prepared for use in the machine of the present invention; Fig. 5 is a transverse sectional view of one side of a shoe illustrating the positions of the parts on a last, as a preparatory step in the method of making the shoe; and Fig. 6 is a similar sectional view of the same shoe after the parts have been permanently secured together and a welt attached. 15

In the manufacture of a shoe, as illustrated, an insole 6 is provided with a lip 8 either by attaching a separate strip or by cutting a channel 10 about the marginal portion of the insole, which channel is inclined from the surface of the insole outwardly. The insole is then fitted to a last indicated in Fig. 5 at 12, an upper 14 is applied to the last, and worked into overlapping relation with the marginal portion of the insole in the usual manner. The side lasting operation of the upper may be performed on side lasting machines of commercial design, examples of which are illustrated in U. S. Letters Patent of Goddu No. 1,796,451 of March 17, 1931, and in an application for Letters Patent of Lawson, Ser. No. 231,750, filed September 26, 1938, preliminary fastening staples 16 being inserted through that portion of the upper margin which is upturned against the lip 8, as illustrated in Fig. 5. The toe and heel seat are then lasted in the manner ordinarily employed in the manufacture of Goodyear welt shoes. 20

To fasten permanently the overlapping marginal portions of the upper and insole, the last is removed from the shoe and the parts are sewed with a through-and-through seam 18, the line of which is guided by the inner surface of the lip. The machine for sewing the lasted upper and insole is of the McKay type, such as illustrated and described in the U. S. Letters Patent of Leveque, No. 1,885,927, dated November 1, 1932, and of Ashworth, No. 1,914,936, dated June 20, 1933, and is provided with a straight hook needle 19, a rotatable work supporting horn 20, a presser-foot 22 acting on the work in line with the seam, and in advance of the point of operation of the needle, and a feed point 24 operating between the presser-foot and the needle. 25

The usual means for guiding a through-and-through seam in a machine of this type consists of an edge gage arranged to engage the upper at the angle where it is bent about the edge of the insole. It frequently is difficult to maintain the 30

angle of the upper against the edge gage, particularly around the shank of the shoe where the angle formed with the insole by the upper is very slight, or where the insole is of light flimsy material. The edge of the shoe may, therefore, slip beneath the edge gage or be held too far from the edge gage by the tension of the upper. In either case, the seam will be improperly located, even to the point of missing the overlapping portions of the insole and upper entirely. Also, with the use of an edge gage variations in thickness of the upper materials caused by the box of the shoe affect the location of a seam adversely. 35

To avoid these difficulties, in the machine of the present invention the edge gage has been dispensed with and a channel guide to cooperate with the inside surface of the lip of the insole has been provided. Where the lip is formed by a separately attached strip, the guide enters the crevice inside the curvature of the lip which is raised above the surface of the insole or where the lip is formed by making an inclined cut in the substance of the insole, the guide enters the cut or channel so formed. 40

The channel guide, indicated at 26, is mounted on the presser-foot 22 which is provided with an opening having a supporting rod 28 secured therein. The rod 28 has a reduced portion, 45 which forms a pivotal axis for the upper end of the channel guide. The lower work-engaging end of the channel guide is formed with guiding surfaces spaced from the seam line and disposed at an acute angle to each other, the apex of which is directed downwardly and to one side towards the point of operation of the needle. The shape of the guiding surfaces, as more clearly illustrated in Fig. 3, is such that when the inner surface of the lip 8 is pressed against the channel guide, there will be a tendency for the guide to be drawn downwardly into the channel or crevice formed by the lip. When the presser-foot is raised during the operation of the feed point the lower end of the channel guide will be held from movement with the presser-foot and the upper end will pivot on the rod 28. To maintain a positive yielding pressure of the channel guide on the insole, a coil spring 30 surrounds the reduced portion of the rod 28, one end of which is bent over the channel guide and the other end engages a pin 32 mounted in the presser-foot, the spring being held in place by means of a screw 34 threaded into the end of the rod 28. For holding the channel guide in place when the work is removed, the upper end of the channel guide has a finger 35 arranged to strike the pin 32. The guide is formed between its ends to provide clearance for both the lip of the insole as well as the inner edge of the upper in case the upper extends beyond the edge of the lip. 50

After being sewn, the lip and that portion of the upper which is turned up during the lasting and stapling operation are trimmed off where it is intended to cement an outsole in place. When trimming the edge of the lip and upper, the bottom of the shoe is held against the rotating cutter or knife of a trimming machine with sufficient pressure to remove the desired amount of the lip and upper and also if desired the staples 16, so that all metal parts may be eliminated which are likely to work their way through the insole into a position where they may injure the foot of the wearer. The location of the seam which joins the upper to the 55 75

insole when guided at a uniform distance from the lip of the insole, according to the present method, insures an ample uniform trimming area between the lip and the stitches of a through-and-through seam. As a result, the staples may be removed more easily while trimming and there will be less liability of injury to the remaining parts of the shoe.

To direct a welt strip 36 into the seam so that an outsole may be secured by stitching to the free outer edge of the welt, the presser-foot 22 is provided with a welt guide 38, the opening of which may be adjusted to the size of the welt by means of a slidably mounted block 40 arranged to be clamped within the opening at the side of the outer welt edge. The lower end of the presser-foot is also formed with a shoulder 42 for guiding the inner edge of the welt to be sewed in contact with the work while the outer edge of the welt is engaged by a flanged block 44 adjustably secured within a slotted extension of the presser-foot. The welt guide is so arranged that the welt strip will be directed towards the point of operation of the needle with the greater portion of the strip which remains free and unattached at the side of the seam line opposite to the channel guide. The presence of the welt, therefore, does not affect the action of the channel guide, and the position of the welt is sewed uniformly out of contact with the lip by the engagement of the channel guide with the lip. When the welt is attached in this manner, parts of the shoe assume the relations illustrated in Fig. 6, so that the lip and staples may be trimmed without danger of disturbing the stitches. It also has been found that by stitching the welt to the marginal portions of the upper and insole with a through-and-through seam instead of a seam passing through the base of the lip, the use of a narrower welt is permissible without decreasing the width at the free edge of the welt which extends beyond the bulge of the shoe upper after attachment. The sole is then completed in the manner of an ordinary Goodyear welt shoe.

When forming a lip on the sole by making an inclined cut or channel at an angle to the surface of the sole, it is customary in making a Goodyear welt shoe to space the cut unequally from the edge along different parts of the insole. According to the manufacture of shoes by the method herein described, it has also been found desirable to cut the channel in this way with the lip closer to the edge of the sole along the forepart of the shoe, and further from the edge along the shank of the shoe, as indicated in Fig. 4. When the lip of the sole is formed in this way, the line of stitching will be guided further from the edge along the shank of the shoe. As a result, the completed shoe, in appearance, simulates a Goodyear welt shoe, but the durability is greater due to the stronger inseam.

Having thus described the invention, what is claimed is:

1. A shoe sewing machine for sewing the overlapping marginal portions of a shoe upper and an insole having a lip, with a through-and-through seam spaced uniformly from and outside of the lip having, in combination, stitch forming and work feeding devices including a straight hook needle, a work supporting horn, a presser foot arranged with the horn to clamp the work in the line of the seam, and a channel guide having its entire work engaging portion located with relation to the needle to act on the

insole inside the lip at the opposite side of the lip from the seam line.

2. A shoe sewing machine for securing the overlapping marginal portions of a shoe upper and an insole with a through-and-through seam, the stitches of which appear at the inside of the shoe and on the outer surface of the upper having, in combination, stitch forming devices including a straight needle, a work supporting horn, a presser-foot arranged to act on the work in the line of the seam, a guide for directing a welt strip towards the point of operation of the stitch forming devices with the greater portion of the strip at one side of the seam line, and a channel guide arranged with its entire work engaging portion acting on the insole at the other side of the seam line.

3. A shoe sewing machine for securing the overlapping marginal portions of a shoe upper and an insole with a through-and-through seam, the stitches of which appear at the inside of the shoe and on the outer surface of the upper having, in combination, stitch forming devices including a straight needle, a work supporting horn, a presser-foot arranged to act on the work in the line of the seam, a feed point for engaging and feeding the work while the presser-foot is raised, and a channel guide mounted for relative movement on the presser-foot as the presser-foot is raised and arranged with its entire work engaging portion acting on the insole at one side of the seam line.

4. A shoe sewing machine for securing the overlapping marginal portions of a shoe upper and an insole with a through-and-through seam, the stitches of which appear at the inside of the shoe and on the outer surface of the upper having, in combination, stitch forming devices including a straight needle, a work supporting horn, a presser-foot arranged to act on the work in the line of the seam, a feed point for engaging and feeding the work while the presser-foot is raised, and a channel guide mounted for relative movement on the presser-foot, as the presser-foot is raised, the work engaging surfaces of said channel guide forming an acute angle the apex of which is directed downwardly and towards the point of operation of the needle.

5. A shoe sewing machine for securing the overlapping marginal portions of a shoe upper and an insole with a through-and-through seam, the stitches of which appear at the inside of the shoe and on the outer surface of the shoe having, in combination, stitch forming devices including a straight needle, a work supporting horn, a presser-foot arranged to act on the work in the line of the seam, a feed point engaging the work along the seam line between the needle and the presser-foot, a guide for directing a welt strip towards the point of operation of the stitch forming devices with the greater portion of the strip at one side of the seam line, and a channel guide mounted for relative movement on the presser-foot at the other side of the seam line and provided with work engaging surfaces forming an acute angle, the apex of which is directed downwardly and towards the point of operation of the needle.

6. A shoe sewing machine for securing the overlapping marginal portions of a shoe upper and an insole with a through-and-through seam, the stitches of which appear at the inside of the shoe and on the outer surface of the shoe having, in combination, stitch forming devices including a straight needle, a work supporting

horn, a presser-foot arranged to act on the work in the line of the seam, a guide for directing a welt strip towards the point of operation of the stitch forming devices to secure the welt to the upper with the outer edge of the strip at one side of the seam line free, a channel guide arranged with its entire work engaging portion acting on the insole at the other side of the seam line, and means arranged adjacent the outer edge of the welt strip for adjusting the size of 10 the opening in the welt guide.

7. A shoe sewing machine for securing the overlapping marginal portions of a shoe upper and an insole with a through-and-through seam,

the stitches of which appear at the inside of the shoe and on the outer surface of the upper having, in combination, stitch forming devices including a straight needle, a work supporting horn, a presser-foot arranged to act on the work in the line of the seam, a feed point for engaging and feeding the work while the presser-foot is raised, and a channel guide pivotally mounted on the presser-foot, and means for pressing the channel guide yieldingly against the surface of the work while the presser-foot is raised.
